SILENT TOGGLE SWITCH

Isidor Attias, Long Beach, N. Y.

Application March 17, 1953, Serial No. 342,923

7 Claims. (Cl. 200—165)

1

The main object of this invention is the provision of a silent toggle switch, that is, a toggle switch which operates silently without the use of mercury.

Another object of the invention is the provision of silently operative circuit-closing and opening means actuated by a silent rocker arm or lever, the said means including a positive make and break member.

The above broad as well as additional and more specific objects will be clarified in the following description, wherein characters of reference refer to like-numbered parts in the accompanying drawing. It is to be noted that the drawing is intended solely for the purpose of illustration and that it is therefore neither intended nor desired to limit the invention necessarily to any or all of the exact details of construction shown except insofar as they may be deemed essential to the invention.

Referring briefly to the drawing,

Fig. 1 is a perspective view of a toggle switch in its housing, illustrating one form in which the switch of this invention may be mounted for installation.

Fig. 2 is a sectional view taken on the line 2—2 of Fig. 1.

Fig. 3 is a sectional view taken on the line 3—3 of Fig. 2.

Fig. 4 is a sectional view taken on the line 4—4 of Fig. 2, showing the switch open.

Fig. 5 is a view similar to Fig. 4, showing the switch closed.

Fig. 6 is a perspective view of the expandable contact element on the rocker arm.

Fig. 7 is a sectional view taken on the line 7—7 of Fig. 3, showing, however, an alternative detail.

Referring in detail to the drawing, the numeral 10 indicates a suitable housing of any desired form or type, having the cover 11 thereof provided with a slot 12 through which the upper or finger end 13 of the rocker arm 14 projects and is longitudinally movable with respect to the slot.

Within the housing there is a compartment 15 into which the arm 14 extends. Approximately intermediate its length the arm has a transverse pin or shaft 16 extending therethrough and projecting from both sides thereof. The ends of the shaft 16 register in recesses 17 cut out of the opposed housing walls 18, near the top thereof. Each wall 18 of the housing has, extending downward from the base of the recess 17, a preferably cylindrical passage 20 in which a coiled com-

2

pression spring 19 registers. Loosely mounted in the spring 19, in the top thereof, is the reduced end of a peg or pin 21 which is urged, by the spring 19, against the adjacent end of the shaft 16, thereby providing frictional pressure against the shaft tending to maintain the same in its position.

Attached to the lower end of the rocker arm 14 is the resilient expandable contact member 22. This comprises a unitary strip of spring metal deformed into the general shape of a U having the two arms joined by the intermediate portion, shown respectively at 23 and 24. The latter has an upwardly extending tab 25 provided with one or more holes 26 therethrough, so that, by means of a screw or screws passed through the opening or openings 26, the member 22 may be secured to the bottom of the arm 14 in the manner illustrated.

20 The two arms 23 of the member 22 are further deformed to provide opposed substantially identical wave-shaped spring members having at their free extremities co-planar opposed legs 27 having a greater length than the depth of the wave-like deformations of the arms 23.

In the lower-left-hand corner of the housing 10 (Fig. 2) a knife-like or wedge-shaped ridge 28 of insulating material, is provided, and this may be integral with the housing, as shown, if desired. It is now apparent that as the rocker is swung from the position shown in full lines in Fig. 2 to that shown in broken lines, the tip edge of the ridge 28 will penetrate between the arms 23 of the member 22 and thus will spread the said arms and cause the legs 27 also to spread.

Imbedded in the walls 18 of the housing, on both sides of the ridge 28, are metallic contact plates 29 provided with electric terminals 30 by means of which the switch is interposed in the electrical circuit. Thus, as the legs 27 are spread, as mentioned above, they will securely contact and engage the plates 29 and thus close the circuit between the plates by means of the member 22.

45 For safer and sturdier construction, the lower end of the arm 14 is provided with a recess in which the contact member, or rather the arms 23 thereof, registers, this recess having the wall 31 extending in front (that is, to the left) of the member 22, Fig. 5, and the walls 32 extending along the sides of the said member, the recess being open, or having no wall, at the rear, or at the right. However, at the junctions of the walls 32 with the wall 31, open spaces 33 are provided through which the legs 27 may project, and the

wall 31 is provided with a central passage 34 through which the ridge 28 may pass through this wall.

The action of the ridge 28 in spreading the two contact arms 23 is obviously silent. In either extreme position of the rocker arm 14, that is, in either the open or closed position of the switch, the arm 14 will be maintained by the spring actuated pegs 21 previously described.

Should it be desirable to provide additional stabilizing means for the rocker 14 in its extreme positions, the shaft 16 may be provided with two adjacent flattened portions 35, as shown in Fig. 7, against which the pegs 21 will contact and engage in each of the said extreme positions of the rocker.

It is apparent from the above that a silent yet sturdy and efficient toggle switch has been provided, eliminating the common and disturbing noisiness of the standard toggle switch.

Obviously, modifications in form or structure may be made without departing from the spirit or scope of the invention.

I claim:

1. A silent toggle switch comprising a housing enclosing a compartment and including opposed side walls, a rocker arm in said housing and extending outward from the housing between said walls, said arm having aligned shaft ends approximately intermediate the length thereof, recesses in said side walls pivotally supporting said shaft ends, resilient means normally resisting rotational movement of said shaft ends, the lower end of said arm having a contact member thereon, said contact member comprising a substantially U-shaped unitary metallic spring band composed of two opposed arms and an intermediate portion joining said opposed arms, said housing having adjacent but spaced from the lower end of said rocker arm a ridge substantially in the plane of pivotal motion of the rocker arm, said contact member being positioned on said rocker arm with the space between the free ends of the arms thereof lying in the plane of said ridge whereby when said rocker arm is swung from a position in which said contact member is clear of said ridge through an arc toward said ridge said ridge penetrates between said free ends of the contact member and spreads the same, said compartment having electric contacts therein on both sides of said ridge, said free ends of said contact member having legs thereon extending outward in opposite directions toward said contacts, said legs upon said spreading of said free ends of said contact member being spread into contact with said electric contacts in said compartment.

2. The toggle switch set forth in claim 1, said opposed arms of said contact member having opposed wave-like deformations therein.

3. The toggle switch set forth in claim 1, said resilient means comprising coiled compression springs, said side walls having passages extending downward therein from the bases of said re-

cesses, said coiled springs registering in said passages and having pegs mounted in the upper ends thereof, said pegs being urged by said springs into contact with said shaft ends.

4. The toggle switch set forth in claim 1, said joining portion of said contact member having a tab extending therefrom, and means for securing said tab to said rocker arm thereby mounting said contact member on the rocker arm.

5. The toggle switch set forth in claim 1, the lower end of said rocker arm having a recess therein having downwardly projecting side walls and a downwardly projecting front wall facing said ridge, said front wall having an opening therethrough for passage of said ridge therethrough, said last-named side walls having openings therethrough for passage of said legs therethrough.

6. The toggle switch set forth in claim 1, said electric contacts comprising metallic plates imbedded in and flush with the opposed side walls of the housing.

7. A silent toggle switch comprising a housing enclosing a compartment and including opposite side walls, a rocker arm in said housing and extending outward from the housing between said side walls, said arm having aligned shaft ends approximately intermediate the length thereof, recesses in said side walls pivotally supporting said shaft ends, resilient means normally resisting movement of said shaft ends, the lower end of said arm having a contact member thereon, said contact member comprising a substantially U-shaped unitary metallic spring band composed of two opposed arms and an intermediate portion joining said opposed arms, said housing having in one corner of said compartment a ridge substantially in the plane of pivotal motion of the rocker arm, said contact member being positioned on said rocker arm with the space between the free ends of the arms thereof lying in the plane of said ridge whereby when said rocker arm is swung from a position in which said contact member is clear of said ridge through an arc toward said ridge said ridge penetrates between said free ends of the contact member and spreads the same, said compartment having electric contact plates therein on both sides of said ridge, said free ends of said contact member having legs thereon extending in opposite directions at right angles to said ridge, said legs upon spreading of said free ends of said contact member being spread into contact with said plates.
